(57) **CLAIM**

The ornamental design for a planter, as shown and described.

DESCRIPTION

FIG. 1 is a perspective view of a planter showing my new design;

FIG. 2 is a front elevational view, with the rear view being a mirror image, thereof;

FIG. 3 is a right side elevational view with the left side being a mirror image thereof;

FIG. 4 is a bottom plan view thereof;

FIG. 5 is a top plan view image thereof; and,

FIG. 6 is an environmental perspective view thereof.

The broken line showing of the plant in FIG. 6 is for illustrative purposes only and forms no part of the claimed design.
